UNITED STATES PATENT OFFICE.

ALFRED STARK, OF CHICAGO, ILLINOIS, ASSIGNOR TO DALLAS BRASS & COPPER CO.,
OF CHICAGO, ILLINOIS, A CORPORATION OF ILLINOIS.

DESIGN FOR A LIGHTING FIXTURE.

60,381.

Specification for Design.

Patented Feb. 7, 1922.

Application filed May 2, 1921. Serial No. 466,230. Term of patent 7 years.

To all whom it may concern:

Be it known that I, ALFRED STARK, a citizen of the United States, residing at Chicago, in the county of Cook and State of Illinois, have invented a new, original, and ornamental Design for a Lighting Fixture, (Case B, No. 11,254,) of which the following is a specification, reference being had to the accompanying drawings, forming part thereof.

Fig. 1 is a side elevation;

Fig. 2 is a partial vertical section of the lower part of the fixture; and

Fig. 3 is a bottom plan view thereof.

I claim:

The ornamental design for a lighting fixture, as shown.

ALFRED STARK.
